(57) **CLAIM**

The ornamental design for a sports novelty item, as shown and described.

DESCRIPTION

FIG. 1 is a front elevational view of a sports novelty item according to the present invention; the back view being a mirror image thereof;

FIG. 2 is a top plan view thereof;

FIG. 3 is a bottom plan view thereof;

FIG. 4 is a left end elevational view thereof; and,

FIG. 5 is a right end elevational view thereof, showing a side opposite that of FIG. 4.

In the drawings, the broken lines represent environmental structure forming no part of the claim.
